MACHINE FOR GRINDING AXLE HOUSINGS OR
THE LIKERichard De Julio, 1064 Sylvan Ave., Bridgeport, Conn.,
and Raymond Piunske, 697 Tunxis Hill Road, Fairfield,
Conn.Filed Aug. 10, 1959, Ser. No. 832,741
2 Claims. (Cl. 51—241)

This invention relates to grinding machinery, and particularly to such machinery which is capable of grinding axle housings without requiring the removal of the axle housing being ground from the vehicle of which it forms a part.

In most land vehicles, particularly heavy ones, such as commercial trucks, a rear axle and differential gear housing is included having tubular ends which are in bearing and sealing relationship with usual drive shafts and/or usual wheels. In usage it is found that wear occurs on the portions of the tubular ends of the housing which support the usual seals, and this results in the seals becoming ineffective, which permits lubricant to leak from within the housing out thereof into the vicinity of the braking structure, thereby resulting in both a loss of lubricant for the differential gears within the housing and a loss in braking ability. Under these circumstances it is conventional practice to disconnect the rear axle and differential housing from the vehicle, send it to a machine shop to be rebuilt, and then to reinstall it on the vehicle. The amount of labor involved in this conventional procedure is approximately thirty-two man hours, in addition to the labor involved in the machine shop. An alternative to rebuilding the housing, of course, is to replace it with a new housing; however, this is extremely expensive and normally considered too costly.

It is an object of the invention to provide an improved grinding machine which is capable of grinding the tubular ends of rear axle and differential housings while the housings are still attached to the vehicle.

The above and other objects and further details of that which we believe to be novel and our invention will be clear from the following description and claims taken with the accompanying drawings, wherein:

FIG. 1 is a fragmentary elevational view, with portions broken away and shown in section for clarity of a representative known wheel and axle assembly;

FIG. 2 is an elevational view, with portions broken away and shown in section, of the FIG. 1 assembly after the wheel and drive shaft thereof have been removed and a grinding machine which incorporates the instant invention has been operatively associated with the rear axle and differential housing;

FIG. 3 is a fragmentary sectional view taken in a plane that passes axially through the tubular end of a rear axle and differential housing after it has been ground and a sleeve applied thereto;

FIG. 4 is an end elevational view looking in the direction of the arrow in FIG. 3;

FIG. 5 is a view similar to FIG. 3 but additionally showing a portion of a wheel and a seal operatively associated therewith;

FIG. 6 is an elevational view of a side of a grinding machine which incorporates the instant invention showing portions of the housing which it is grinding in dot-dash lines, and

FIG. 7 is an end elevational view looking in the direction of the arrow in FIG. 6.

In FIG. 1 there is illustrated a representative, known wheel and axle assembly. It should be understood that the precise construction of the wheel and axle components is not critical as regards our invention, just so long as the rear axle and differential housing includes a cylindrical

2

surface which supports a seal and which is subject to wear in use. The rear axle and differential housing is generally designated by reference numeral 10 and comprises a central, spherical, hollow, enlarged, differential gear housing portion 12 and a pair of coaxial, oppositely extending, tubular ends 14; the entire housing 10 is not illustrated in FIG. 1, there being only one tubular end 14 shown. However, it should be understood that the housing 10 includes another tubular end of similar construction to the one illustrated, and that description of the illustrated tubular end and its associated elements equally applies to the unillustrated tubular end.

Within the tubular end 14 there is mounted a cylindrical bearing sleeve 16 which has a portion 18 that projects axially beyond the extremity of tubular end 14. Rotatably mounted within the bearing sleeve 16 is an elongated, cylindrical, drive shaft 20 having its inner end of known construction for cooperating with the differential gears in the housing portion 12. An end 22 of the drive shaft 20 extends axially beyond the bearing sleeve portion 18 and has a wheel mounting flange 24 formed at its extremity. Flange 24 is disk-like and may be rigidly and permanently connected to the drive shaft 20, as by being welded at 26.

A wheel, the hub 28 which is illustrated, is rigidly connected to the drive shaft flange 24 so as to be drivingly connected thereto and to rotate therewith in unison, as by having bolts 30 pass through appropriate openings (unnumbered) in the drive shaft flange and securely seat in threaded bores 32 formed in the wheel hub. The wheel hub 28 has a substantial, axially extending, cylindrical, internal bearing surface 34, formed by a passage that extends centrally therethrough, which has rotary bearing contact with the cylindrical, external, bearing surface 36 of the bearing sleeve 16. The inner axial end of the wheel hub 28 has a plain, cylindrical counterbore 38 formed therein which communicates with the passage that forms the bearing surface 34. Counterbore 38 forms an inwardly facing, cylindrical surface 40 and a flat, radially extending shoulder 42 on the wheel hub 28.

The housing tubular end 14 has a step 44 formed at its extremity which, in turn, forms an external, cylindrical, radially outwardly facing surface 46 and a flat, radially extending shoulder 48. When fully assembled, as illustrated in FIG. 1, the axial extremity of the housing tubular end 14 is disposed within the counterbore 38 of the wheel hub 28, and these parts cooperate to define an annular cavity in which is mounted an annular seal 50. Seal 50 may be of any suitable known type and is particularly designed to prevent leakage of lubricants.

When fully assembled, the drive shaft 20 is arranged to be rotatably driven through the differential gears in the housing portion 12 and to, in turn, rotatably drive the wheel hub 28 and the remainder of the wheel. During such operation, the external cylindrical surface 52 of the drive shaft 20 is in rotary bearing contact with the internal cylindrical bearing surface 54 of the bearing sleeve 16, and the internal cylindrical bearing surface 34 of the wheel is in rotary bearing contact with the external cylindrical bearing surface 36 of the bearing sleeve 16. Adjacent portions of the wheel hub 28 and the housing tubular end 14 are also in bearing contact. However, the primary operational aspect of these parts is to provide a cavity for the seal 50 which effectively prevents the escape of lubricant which exists within the housing 10 and which lubricates the various bearing contacting surfaces discussed above. With regard to completing the sealing of the assembly in FIG. 1, it will be understood that it is a simple matter to provide an effective lubricant seal between the drive shaft flange 24 and the portion of the wheel hub 28 to which it is connected.

In use it has been found that the seal 50 is inclined to

rotate with the wheel hub 28, and therefore, that wear occurs on the external cylindrical surface 46 of the housing tubular end 14. As was pointed out above in the introduction to this specification, when a sufficient amount of this wear occurs, the effectiveness of seal 50 is impaired and lubricant tends to leak past the seal 50; this leakage results in both loss of lubricating effectiveness because of the diminution of the amount of lubricant and the loss of braking ability because the leaking lubricant is prone to seep onto the brake drum. The usual procedure, prior to our invention, to correct this condition was to either rebuild or replace the housing 10, and in either event an inordinate amount of labor was involved in order to disconnect the housing 10 from the vehicle and replace it with a repaired or a new housing.

With our invention, the wheel and axle assembly may be restored to its original condition of sealing effectiveness by grinding the external cylindrical surface 46 of the housing tubular end 14 and then applying a sleeve onto the ground external cylindrical surface 46. In doing this, the outer diameter of the sleeve 56 is selected to be the same as the original outer diameter of the external cylindrical surface 46 and the outer diameter of the the ground cylindrical surface 46G is ground so as to snugly receive the sleeve 56. After the sleeve 56 is mounted on the housing tubular end 14, the seal 50, or a replacement therefor, the wheel and the drive shaft are reassociated with the housing 10, as illustrated in FIG. 5. At this time, the original sealing effectiveness of the seal 50 has been restored.

Our improved grinding machine generally comprises means for mounting the entire machine operatively relative to the housing to be ground, a rotatable grinding tool disposed to contact the cylindrical portion of the housing to be ground, a powered means for the rotating the grinding tool, carrier means which is rigidly supported by the mounting means and which, in turn, selectively adjustably supports the grinding tool and powered means relative to the housing, and selectively manually operable means for rotating the entire machine about the housing.

The mounting means (see FIGS. 6 and 7) may conveniently take the form of a clamp-type split sleeve which comprises two semi-cylindrical sections 58, each of which has two pairs of spaced, oppositely extending tabs 60. The tabs 60 are disposed in such a manner that four pairs of associated mounting tabs are formed, each pair of which is adapted to receive a bolt 62, so as to render the sections 58 manually radially adjustable toward and away from each other. In order to effect this arrangement and to mount the bolts 62, one tab 60 of each pair of mounting tabs includes a plain opening 64 and the other tab thereof includes a threaded opening 66. Integrally formed with the sections 58 is a hand wheel 68 which comprises a circular rim that is adapted to be gripped manually by a user, and a plurality of integrally formed, radial spokes 70 which are integrally connected to the sections 58. The hand wheel 68 comprises a selectively manually operable means for rotating itself, the sections 58 and the remainder of the machine which is supported by the sections 58.

Rigidly secured to the upper sections 58 (with reference to FIGS. 6 and 7) is an elongated, plate member 72. The plate member 72 extends generally horizontally and is longitudinally centrally thereof rigidly and permanently secured to the upper section 58, as by the welds 74. At one end of the plate member 72, said plate member is pivotally connected by the hinge 76 to a second plate member 78. The free end 80 of the plate member 78 is of reduced width and is bent so as to be approximately parallel to the plate member 72. An oblong slot 82 is formed in the free end 80. The free end 84 of the plate member 72 is of reduced width and includes an oblong slot 86. The free end 84 supports a slightly downwardly extending small plate 88, as by

having a screw 90 pass through an end of the plate 88 and be anchored in a threaded opening 92 in the free end 84. An elongated rod 94, which is threaded at both of its ends 96, 98, is operatively associated with the free ends of the plate members. The threaded end 98 passes through the slot 86 and is threaded into a pair of associated nuts 100 which are disposed adjacent the free end of the plate 88. The threaded end 96 passes through the slot 82 and threadededly receives an adjustable feed nut 102. Concentrically disposed about the central portion of the rod 94 in contact with and between the free ends of the plate members is a strong compression spring 104. The plate members 72 and 78 and the rod 94, spring 104 and their associated parts comprise the carrier means for the grinding tool and its powered means.

The grinding tool comprises a disk-like grinding wheel 106 made of an appropriate abrasive material and appropriately shielded by a generally semi-circular shield 108, and the powered means comprises an electric motor 112. The grinding wheel 106 is rigidly mounted on the drive shaft 110 of the electric motor 112 for joint rotation therewith. The precise mountings of the grinding wheel and the shield 108, and the precise construction of the motor 112 is not critical to our invention. The motor 112 is exemplary of a powered means which supports and drivingly rotates the grinding wheel 106. The motor 112 is rigidly secured to the plate member 78, as by having a plurality of mounting feet 114 bolted to the plate 78 by nut and bolt assemblies 116 or other equivalent securing means. It will, therefore, be understood that the powered means, in the form of electric motor 112, and the grinding tool, in the form of grinding wheel 106, are both carried by the plate member 78.

The grinding wheel 106 is mounted by the carrier means for selective adjustment radially relative to the work, i.e. the housing. Such adjustment is attained by manually turning the feed nut 102 either clockwise or counter-clockwise, depending upon the radial direction of adjustment of the grinding wheel desired. By reference to FIG. 7 it will be observed that the plate members 72 and 78 are hinged to each other at adjacent ends by the hinge 76 and generally define a V, and that the free ends 80 and 84 of these plate members are spaced apart by the rod 94, the spring 104 and their associated parts which cooperate to form an adjusting mechanism. The arrangement of the adjusting mechanism and the strength of the spring 104 are such that the spring constantly biases the free ends 80, 84 away from each other. The actual distance the free ends are spread by the spring 104 is determined by the positions of the uppermost nut 100 on the threaded rod end 98 and the feed nut 102 on the threaded rod end 96. In other words, the spring 104 tends to spread the free ends 80, 84 to the maximum limit permitted by the positions of the upper nut 100 and the feed nut 102. In order to close the free ends 80, 84, i.e. reduce the distance they are spread apart, the feed nut 102 is rotated in a direction to move on the rod threaded end 96 toward the threaded end 98. With reference to FIGS. 6 and 7, closing the free ends will result in both the electric motor 112 and grinding wheel 106 being moved generally vertically downwardly. Turning of the feed nut 102 in the opposite direction results in its movement in the opposite direction and spreading of the free ends by the spring 104; such action results in movement of the electric motor 112 and grinding wheel 106 generally vertically upwardly. Therefore, it will be understood that the carrier means permits the selective manual adjusting of the vertical position of the grinding wheel 106.

When it is desired to grind a worn external cylindrical surface of a housing tubular end, such as the surface 46 in FIGS. 1 and 2, the wheel hub 28 and its wheel, the seal 50 and the drive shaft 29 are removed from the housing 10. This leaves the housing 10 and the bearing sleeve 16 remaining, and as is shown in FIGS. 2, 6 and 7, our improved grinding machine is operationally associated

with the housing 10 and bearing sleeve 16 to grind the surface 46. This operative association is effected by mounting the split sleeve sections 58 about the projecting end 18 of the bearing sleeve, as by separating them radially and sliding them on the projecting end, adjusting the entire machine axially until the grinding wheel 106 is disposed in the step 44, and then tightening the sections 58. After tightening, the sections 58 are mounted by the bolts 62 so as to have a fit on the bearing sleeve end 18 which is fairly tight but yet which permits rotation of the sleeve sections 58 relative to the bearing sleeve end 18, by the exertion of a reasonable amount of manual rotary force (which can conveniently be applied selectively by the user grasping the hand wheel 68 and turning it).

The manual turning of the hand wheel 68 is performed while the grinding wheel 106 is drivingly rotated by the electric motor 112 which is energized during a grinding operation. Turning of the hand wheel 68 results in grinding the cylindrical surface 46. The precise amount of the material that forms cylindrical surface 46 which is ground off is determined by the user adjusting the feed nut 102 successively during the grinding operation to thereby move the grinding wheel 106 radially inwardly relative to the work. In practice it has been found that it is necessary to grind approximately one-eighth of an inch off of the cylindrical surface 46 to form surface 46G. When this is accomplished, the cylindrical surface 46 has been reduced to the ground surface 46G shown in FIGS. 3-5, and the sleeve 56 is then forced on the surface 46G. The sleeve is dimensioned so that it tightly fits thereon, and has an external diameter which is substantially the same as the original external diameter of the cylindrical surface 46. The drive shaft 20, wheel hub 28 and its wheel, and the seal 50 are then remounted on the housing 10 and bearing sleeve 16 into their FIG. 5 disposition, wherein the sealing effectiveness of the assembly has been restored.

In practice it has been found that with our improved grinding machine it is possible to perform the necessary corrective work on a rear axle and differential housing having a worn external cylindrical seal seating surface in approximately three man hours, compared with the heretofore required thirty-two hours, approximately. The economy produced by our invention in the reduction of man hours required to effect repair should be apparent. However, just as important as the direct reduction in labor time is the reduction in time that the vehicle which is being repaired is incapacitated. The real importance of this will be fully understood when it is realized that these vehicles usually are trucks, and that it is important to maintain such commercial vehicles in operating condition the maximum amount of time.

As will be evident from the foregoing description, certain aspects of our invention are not limited to the particular details of construction of the examples illustrated, and we contemplate that various and other modifications and applications will occur to those skilled in the art. It is, therefore, our intention that the appended claims shall cover such modifications and applications as do not depart from the true spirit and scope of our invention.

What we claim as new and desire to secure by Letters Patent of the United States is:

1. A machine for grinding a cylindrical surface on an axle housing or the like while still mounted on a vehicle comprising: a clamp-like split sleeve for operatively mounting the machine relative to the work; said split sleeve being mounted for selective rotation relative to and about an axis which is coaxial with the work; a hand wheel rigidly secured to said split sleeve for selectively manually rotating said split sleeve; an elongated first

member longitudinally centrally rigidly secured to said split sleeve and extending generally horizontally; an elongated second member pivotally secured at one of its ends to an end of said first member; a rotatable grinding tool arranged to operatively engage the periphery of the work; powered means for rotating said grinding tool; said grinding tool and said powered means supported by said second member, and means connecting the free ends of said first and second members in such a manner that they are selectively adjustable so as to close or separate and thereby cause movement of said grinding tool radially relative to said work.

2. A machine for grinding a cylindrical surface on an axle housing or the like while still mounted on a vehicle comprising: means for operatively mounting said machine relative to the work to be ground; said mounting means being mounted for selective rotation relative to and about an axis which is coaxial with the work, a rotatable grinding tool arranged to operatively engage the periphery of the work; powered means for rotating said grinding tool; carrier means for supporting said grinding tool and said powered means; said carrier means being supported by said mounting means and selectively adjustable to adjust the position of said grinding tool radially relative to the work, and means for selectively rotating said mounting means about its axis whereby said grinding tool is moved angularly relative to the axis of the work and describes a surface of revolution about said axis; said carrier means comprising an elongated first member which is rigidly secured to said mounting means, an elongated second member which is pivotally secured to said first member and which cooperates therewith to form a V, and mechanism for selectively adjusting the position of said second member relative to said first member by causing pivoting therebetween, and said second member carrying said grinding tool and said powered means, whereby selective adjustment of said second member results in movement of said grinding tool radially relatively to the work and thereby sets the position of said grinding tool for operation; said mechanism comprising an elongated adjusting member that is operatively associated with the free ends of said first and second members so as to be selectively utilized to cause separation or closing of said free ends and thereby adjust the position of the second member relative to the first member, said elongated adjusting member being threaded at both ends and having one of its ends anchored to the free end of one of said members which forms a V and a portion of its other end extending through an opening in the free end of the other of said members, a compression spring that is disposed about said adjusting member and is in biasing separating contact with both of said free ends, and an adjusting nut that is threadedly mounted on said portion of the other end of said threaded member and arranged for axial movement relative thereto to selectively either manually overcome the bias of said spring and cause closing of said free ends or permit said spring to expand and cause separation of said free ends, depending upon the direction of axial movement of said adjusting nut.
